SHIPPING RIG

Otto E. Haverlandt, Jr., Great Falls, Mont., assignor to Bison Manufacturing Company, Great Falls, Mont., a corporation of Montana

Application November 19, 1948, Serial No. 60,930

3 Claims. (Cl. 206—46)

1

This invention relates to the packaging and shipment of articles of commerce and more particularly, relatively heavy articles such as internal combustion engines and the like.

Specifically, the invention relates to a shipping rig for application to the motor block of an automobile or other internal combustion engine and replacing certain necessary parts during shipment thus, among other things, simplifying shipment and reducing the weight and size of the crated article.

Increase in transportation rates has made it necessary to reduce the weight of the shipments if the costs are not to be prohibitive. In the shipment of internal combustion engines as, for example, an automobile engine, ordinarily the engine is crated requiring labor and material, and the completed crate weighs approximately 100 lbs., which is a substantial consideration insofar as cost is concerned. Likewise the time consumed in crating an engine is an important factor. The crates are capable of being used only a relatively few times, and frequently parts that should be protected are permitted to be exposed and are damaged during shipment.

With conventional crates about $\frac{1}{6}$ of the floor space is wasted and crating requires labor skilled at least to a substantial degree.

Another objection is that the conventional crate must be removed within 30 days in order to be able to determine whether or not the contents have been damaged in transit. This increases labor costs, particularly when the contents are not needed immediately, but is necessary if damage is detected and claim made for reimbursement therefor.

It is an object of the invention to provide a package for shipment which is of reduced size and weight, requires less labor, material, time and consequent expense and which will protect from dust, dirt, moisture and damage in shipment, during storage, or in fact until it is used.

Further objects and advantages of the invention will be apparent from the following description taken in conjunction with the accompanying drawings, wherein:

Fig. 1 is a perspective of the shipping rig including the false oil pan, valve chamber, and bell housing cover of the present invention;

Fig. 2, an end view of the engine block with the bell housing cover and having the shipping rig as illustrated in Fig. 1 applied thereto;

Fig. 3, a top plan view; and

Fig. 4, a bottom plan view.

Referring to the drawings, there is disclosed a

2

motor block 10 of conventional construction having cylinder heads 11 adapted to be held in position by means of fastening elements in the form of head bolts 12, each head having an intake manifold 13. A valve chamber housing, not shown, is adapted to be secured on the cylinder block between the cylinder heads by additional bolts 12. The motor block is also provided with a bell housing 14 for receiving the fly wheel and starter mechanism, to which bell housing the clutch housing is secured by means of bolts 15.

In accordance with the present invention, in order to reduce the weight, time, labor, space, and cost of shipment there is provided a shipping rig 15 for providing a package which includes in addition to the motor block and cooperating elements for shipment a valve chamber cover, an oil pan, and a bell housing closure all for attachment to the motor block to protect and support the same 20 during shipment and storage.

The shipping rig is applicable to the motor block and the added parts include curved and plate-like bodies including a valve chamber cover 16 which is a relatively thin, inexpensive, plate-like body having apertures 17 disposed according to the location of some of the fastening bolts 12, only there being fewer apertures 17 so that by using a minimum number of fastening bolts in the opposite ends of the plate the latter can be firmly and quickly secured in position, or removed.

A substantially semi-cylindrical body is adapted to fit on the under side of the motor block in lieu of the conventional oil pan for protecting the crank shaft and connecting rods or other parts of the motor which would normally be exposed. The substantially semi-cylindrical oil pan 18 is provided with outwardly turned flanges 19 having openings 20 for receiving the conventional oil pan holding bolts 21. When the engine is in upright position it rests on the surface of the semi-cylindrical oil pan 19 from end to end.

In order to provide triple supporting means to prevent the motor block and rig from rolling over or upsetting, a bell housing cover 22 of 45 relatively thick laminated construction such as plywood or the like may be employed. This bell housing cover is provided with openings 23 for the reception of bolts 15, and when in the position shown in Figs. 2, 3, and 4, transversely of the semi-cylindrical pan 18 its lower intermediate portion is substantially in the plane of the lowermost curved supporting portion of the semi-cylindrical pan 18 with the portions of the edge of the bell housing cover extending toward the ends of the same from its center, forming two ad-

ditional supporting portions thereby supporting the motor block solidly and against rocking or upsetting.

If desired, and to prevent separation or possible loss of one of the parts of the novel shipping rig, each of the three elements thereof may be provided with an eye or the like 25 intended for engagement with a link of the chain 24 as will be more readily apparent from an examination of Fig. 1 of the drawing. The three elements may thus be maintained as a unit when detached from a motor block.

It will be apparent from the foregoing that with the shipping rig of the present invention a substantial improvement in the crating of a motor block is accomplished, which not only reduces the space of the crated block substantially 90%, but permits damage in shipment to be readily detected, reduces the cost of material, labor and time involved, as well as the weight of the crated article and the cost of the same. Also, the valve chamber cover plate forms a ready flat receiving surface for the name of the shipper and addressee.

It will be obvious to those skilled in the art that various changes may be made in the invention without departing from the spirit and scope thereof and therefore the invention is not limited by that which is shown in the drawings and described in the specifications but only as indicated in the appended claims.

What is claimed is:

1. A shipping package comprising a motor block provided with openings in the top and bottom walls and a bell housing on one end wall thereof, the wall structure defining said openings and bell housing being provided with spaced apertures for fastening elements, a relatively thin semi-cylindrical shell having substantially radially disposed longitudinal flanges provided with spaced apertures located for alignment with certain of the apertures in the bottom wall of the motor block, fastening elements engaged in said aligned apertures for securing said shell to said motor block so that the weight of the block will be sustained upon said shell, a relatively thick plate-like body laminated for strength and provided with spaced apertures located for alignment with certain of the apertures in the end wall of the block, fastening elements engaged in said aligned apertures for securing said plate-like body in position transversely of the shell with the lower edge of said body adjacent the center thereof in substantial alignment with the supporting surface of said shell and with portions of said lower edge extending toward the ends of the plate-like body forming two additional supporting portions for said block, a second plate-like body provided with apertures located for alignment with certain of the apertures in the top wall of said block, and fastening elements engaged in said aligned apertures for securing said second plate-like body to said block to provide a cover for the opening in the top wall thereof.

2. A shipping package comprising a motor

block provided with openings in the top and bottom walls and a bell housing on one end wall thereof, the wall structure defining said openings and bell housing being provided with spaced apertures for fastening elements, a relatively thin semi-cylindrical shell having substantially radially disposed longitudinal flanges provided with spaced apertures located for alignment with certain of the apertures in the bottom wall of the motor block, fastening elements engaged in said aligned apertures for securing said shell to said motor block so that the weight of the block will be sustained upon said shell, a relatively thick plate-like body laminated for strength and provided with spaced apertures located for alignment with certain of the apertures in the end wall of the block, fastening elements engaged in said aligned apertures for securing said plate-like body in position transversely of the shell with the lower edge of said body in substantial alignment with the supporting surface of said shell to support said motor block in upright position, a second plate-like body provided with apertures located for alignment with certain of the apertures in the top wall of the motor block, and fastening elements engaged in said aligned apertures for securing said second plate-like body to said block to provide a cover for the opening in the top wall thereof.

3. A shipping package comprising a motor block provided with openings in the top and bottom walls and an opening in one end wall thereof, the wall structure defining said openings being provided with spaced apertures for fastening elements, a substantially semi-cylindrical shell having substantially radially disposed longitudinal flanges provided with spaced apertures located for alignment with certain of the apertures in the bottom wall of the motor block, fastening elements engaged in said aligned apertures for securing said shell to said motor block so that the weight of the block will be sustained upon said shell, a plate-like body provided with spaced apertures for alignment with certain of the apertures in the end wall of the block, fastening elements engaged in said aligned apertures for securing said plate-like body in position transversely of the shell with the lower edge of said body in alignment with the supporting surface of said shell to support said motor in upright position, a second plate-like body provided with apertures located for alignment with certain of the apertures in the top wall of the motor block, and fastening elements engaged in said aligned apertures for securing said second plate-like body to said block to provide a cover for the opening in the top wall thereof.
